DESIGN FOR A FROZEN FOOD CABINET

Milton Rifkin, Chicago, Ill., assignor to Frez-O-Mat Sales Corporation, Chicago, Ill.

Application March 26, 1946, Serial No. 127,976

Term of patent 14 years

(Cl. D80—11)

To all whom it may concern:

Be it known that I, Milton Rifkin, a citizen of the United States of America, residing at Chicago, in the county of Cook and State of Illinois, have invented a new, original, and ornamental Design for Frozen Food Cabinets, of which the following is a specification, reference being had to the accompanying drawing, forming part thereof.

The drawing illustrates a perspective view of a frozen food cabinet showing my new design.

I claim:

The ornamental design for a frozen food cabinet, as shown.

MILTON RIFKIN.
